ARC RUPTURING DEVICE FOR ELECTRIC
SAFETY FUSES

Emil Lange, Berlin-Zehlendorf, Germany

Application March 23, 1937, Serial No. 132,583
In Germany March 27, 1936

3 Claims. (Cl. 200—120)

This invention relates to a safety fuse for high tension electric currents and of the kind wherein fuse wires which connect the terminals of an enclosing casing are adapted, on fusing, to form 5 one arc at a narrow outlet in the casing and another arc in a space the fluid contents, of which, on being heated by the arc, causes the fluid outside the space to be ejected through the outlet for rupturing the arc.

10 Fuses of this kind have the property of taking up the full strength of the short-circuit current, and it is therefore necessary to make the structure of dimensions capable of coping with the largest currents that can be expected.

15 The object of the present invention is to obtain a construction which allows the fuse to be of comparatively small dimensions, and the invention consists essentially in providing the casing with a resistor having one terminal permanently connected to the fuse circuit and another terminal arranged so as to attract and make contact with one of the arcs on the fusing of the wires, thereby reducing the current flowing through the arcs.

20 Fig. 1 of the accompanying drawing represents a sectional view of a fuse constructed according to the invention, and

Fig. 2 is a sectional view a modified form.

Referring first to Fig. 1 it will be seen that the 25 fuse structure comprises an insulating casing 1 which is closed at one end by a cap 108 forming one terminal of the fuse. The other end of the casing is fitted with an insulating member 2 having a central, narrow opening forming an outlet 3 for the fluid in the casing. The outlet also forms a seating for a spring pressed valve 110 whereby said outlet is normally closed. An annular metallic member 109 surrounding the outlet forms the second terminal of the fuse. Supported centrally within the casing 1 is a tubular insulating member 3 one end of which faces the outlet and is closed by an insulating member 106. A metal conductor 105, fitted in the insulating member 106, forms a contact member between two fuse wires 104 and 103. The wire 104 is attached to the terminal 109, and the wire 103 is attached to the terminal cap 108.

30 On the fusing of the wires one arc will be formed between the connecting member 105 and the terminal 109, and another arc will be formed inside the member 3. The fluid contained in the space 102 of the latter will be expanded by the heat and cause the colder fluid in the outside 35 space 101 to be ejected through the narrow out-

let, thereby causing an effective rupturing of the arc formed at the outlet.

According to the invention a tubular resistor 111 is arranged within the member 3 with one end in contact with the connecting member 105 5 through the medium of washers 113 of copper or other good conducting material. The opposite end of the resistor is fitted with a similar washer 112, and the central space 114, through which the wire 103 passes, is fitted with a lining 115 of 10 asbestos or other insulating material, the resistor being thus enclosed in insulation except for the free end thereof to which the copper washer 112 is connected. Thus, when the wire fuses, the arc will be attracted by and connect 15 with the resistor through the metal washer 112, and the current flowing through the arc at the outlet will therefore be reduced in strength. Consequently the pressure curve, which follows the rising strength of the current, will not attain 20 the value of the entire short-circuit current.

Fig. 2 shows a construction in which the resistor 121 is arranged so as to form the outlet of the fuse casing 4. A central tubular member 5, supported as previously described, carries in 25 a closing member 6 of insulating material a conductor 118 which forms a connecting member between the fuse wires 117 and 119. The latter passes through a lateral duct in the resistor 121 for connection to an annular terminal 120 mounted 30 so as to be exposed at the side of the casing 4. A cap 7, which surmounts the casing 4, is provided with gas outlets 123 and guides a spring controlled valve 122 which normally closes the outlet of the resistor 121.

35 On the fusing of the wires, the arc formed at the outlet of the casing will be attracted by and connect with the resistor forming said outlet, and the current will be correspondingly reduced.

By a proper dimensioning of the resistor, the 40 current allowed to pass through can be determined, and excessive values of such current can thus be obviated. This allows a reduction in the size of the fuse structure and also prevents the rupturing of the arc from being retarded by a 45 too strong current.

I claim:

1. An electric safety fuse of the character described comprising an insulating casing containing a fluid and having at one end thereof a narrow outlet for said fluid, a contact member at each end of the casing, a confined space in said casing communicating with the outlet through a circuitous route, fuse wires connecting the contacts through the outlet and through said space 55

so that, on a fusing of the wires, arcs will be formed at the outlet as well as in said space, and so that the heating of the fluid in the latter will cause the fluid outside the space to be ejected through the outlet for rupturing the arc, and a resistor having one terminal permanently connected to the fuse circuit and another terminal arranged in position to attract and connect with one of the arcs for reducing the strength of the current.

2. An electric safety fuse of the character described comprising an insulating casing containing a fluid and having at one end thereof a narrow outlet for said fluid, a contact member at each end of the casing, a confined space in said casing communicating with the outlet through a circuitous route, a pair of fuse wires arranged

in series and connecting the contacts through the outlet and through said space so that, on a fusing of the wires, arcs will be formed at the outlet as well as in said space and so that the heating of the fluid in the latter will cause the fluid outside the space to be ejected through the outlet for rupturing the arc, a rigidly supported, insulated member connecting the two wires, and a resistor in said space having one end in permanent connected contact with said connecting member and a free end arranged in position to attract and connect with the arc formed in said space for reducing the strength of the current.

3. A structure as claimed in claim 1 wherein the resistor forms an outlet passage for the casing. 15
